US0D1073394S

(12) **United States Design Patent** (10) **Patent No.:** **US D1,073,394 S**
(45) **Date of Patent:** **** May 6, 2025**

(54) **GRINDER**

(71) Applicant: **NINGBO CHEFSHERE KITCHEN TECHNOLOGY CO., LTD.**, Zhejiang Province (CN)

(72) Inventor: **Guoping Zhang**, Zhejiang Province (CN)

(**) Term: **15 Years**

(21) Appl. No.: **29/882,506**

(22) Filed: **Jan. 16, 2023**

(30) **Foreign Application Priority Data**

Oct. 25, 2022 (CN) 202230704086.1

(51) **LOC (15) Cl.** **31-00**

(52) **U.S. Cl.** ..... **USPC D7/372; D7/414**

CLAIM

The ornamental design for a grinder as shown and described.

DESCRIPTION

FIG. 1 is a front elevational view of a grinder showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof; and,

FIG. 8 is a front elevational view in an alternative configuration.

The broken lines showing portions of the grinder and environmental structure form no part of claimed design.

1 Claim, 8 Drawing Sheets
